(57) **CLAIM**

The ornamental design for a barbecue grill clip, as shown and described.

DESCRIPTION

FIG. 1 is a top perspective view of a barbecue grill clip showing our new design;

FIG. 2 is another top perspective view thereof showing the clip in an open position;

FIG. 3 is a front elevational view thereof;

FIG. 4 is a side elevational view thereof;

FIG. 5 is a rear elevational view thereof;

FIG. 6 is a top plan view thereof; and,

FIG. 7 is a bottom plan view thereof.

The broken lines showing of a spring and a spring support post are for illustrative purposes only; the broken lines form no part of the claimed design.
